6 Claims. (Cl. 62—115)

1

The present invention relates to high performance refrigerating apparatus.

Refrigerating apparatus of the type under consideration in the present disclosure employs a closed refrigerating circuit through which passes a refrigerating agent such as methyl chloride (CH_3Cl) or one of the so-called freon gases such as dichloro-difluoromethane (CCl_2F_2). The refrigerating agent passes from a closed tank to an evaporator in which it is evaporated by expansion and from which it passes to and is compressed in a compressor and after being condensed by passing through a condenser is returned to the tank; it being possible to employ the condenser itself as the tank.

One of the objects of this invention is to improve the performance of refrigerating apparatus of this type by providing circuit regulating devices which make it possible to obtain an increase in the refrigerating effect thereof.

It is a more particular object of this invention to provide regulators or expanders for the circuit that permit the maintenance at a constant and determined value of the suction pressure in the evaporator circuit, an increase in the refrigerating effect per unit of refrigerant in the system, and the obtaining of a substantially maximum cooling effect from the evaporator.

In a refrigerating circuit incorporating the features of this invention, the liquid coming from the storage tank passes into a cooling circuit previously disposed around a cold expansion chamber which forms part of the pressure responsive regulator and is in communication with the evaporator. The low temperature prevailing in this cold chamber cools the liquid coming from the tank into this preliminary cooling circuit and this insures expansion of the refrigerating fluid to a lower point of the refrigerating cycle, with resultant decrease in the heat content of the refrigerant just before it enters the expansion valve, and consequent increase in its refrigerating effect within the evaporator.

An expander in accordance with this invention comprises a channel or part controlled by a pressure responsive bellows that maintains constant the suction pressure of the refrigerating fluid leaving the evaporator. The bellows is disposed within a chamber around which there is placed a portion of the circulatory circuit of the fluid before it passes through the part and in this chamber there is provided an arrangement which increases the refrigerating effect of the system. It also prevents the formation of frost at the joint which is located between the body of this chamber

2

and the cap or bell of the expander owing to the fact that this joint is then at a point in the circuit where the fluid is still tepid. A thermostatic bellows that by its control insures a better performance of the evaporator may be incorporated in this expander. This bellows is provided with means for limiting its travel or movement and with a thermostatic bellows control connection. The packing that insures the tightness of the bell of the expander is arranged in such a way as to permit axial control of a rod which regulates the travel of one and/or the other of the bellows.

These as well as other features of this invention will be more fully understood from the following detailed description of a plurality of embodiments thereof as illustrated in the attached drawings.

This invention resides substantially in the combination and construction, arrangement and relative location of parts as will be described in detail below.

In the accompanying drawings,

Figure 1 is a diagrammatic and schematic view of a refrigerating circuit incorporating features of this invention;

Figure 2 is a cross-sectional view showing the construction of one form of expander in accordance with this invention;

Figure 3 is a cross-sectional view of another embodiment of an automatic expander without thermostatic control in accordance with this invention.

The refrigerating circuit shown schematically in Figure 1 comprises a tank 1 of refrigerating fluid in liquid state under pressure. This tank is connected by a pipe 3 to the expander, generally indicated by the reference numeral 2. The connection 3 terminates in preliminary cooling coil 4 mounted within the casing of expander 2, preferably surrounding the chamber 5 into which the fluid is discharged from the preliminary cooling coil through the port 12. The port is controlled by the valve 13, which will be referred to later.

The fluid, after expanding through the port 12 into the chamber 5, is conducted therefrom through the pipe connection 6 into the evaporator 7. It is now in a state of low pressure and comprises a liquid vapor mixture. At the outlet of the evaporator 7 the fluid is in the form of a superheated vapor and is transmitted by a pipeline 8 to the intake valve of the compressor 9. It is delivered from the compressor in the form of a vapor of high pressure and is passed by means of the pipe connection 10 to the condenser 11. It is converted in the condenser into a high pres-

sure liquid and then passes directly into the high pressure refrigerating liquid storage tank 1.

The expander 2, which includes the expansion chamber 5 and the preliminary cooling circuit 4, includes a double, pressure-responsive and thermostatic control which will now be described in greater detail. The needle valve 13 which controls the port 12 is normally held against the port so as to keep it closed by the action of spring 14 which acts in the same direction on the pressure-responsive bellows 16 by means of the rigid mechanical connection 15. The pressure-responsive bellows 16 is subjected on one side to the pressure in chamber 5, of which it forms a wall, in addition to the pressure of spring 14, and is exposed to atmospheric pressure on its other side, since this condition prevails in the cap or bell 17 of the expander. It is also subjected to the regulated pressure of the spring 18 and of the bellows 20 transmitted to it by the rigid mechanical connection 19. Since the atmospheric pressure which prevails in the bell 17 is assumed to be constant, if the evaporator pressure falls below a predetermined value, controllable by the spring 18, the sum of the pressures of the atmosphere and of spring 18 on the pressure-responsive bellows 16 will become greater than the sum of the pressure in chamber 5 and that of spring 14. Since the balance of the pressures on its two faces is thus upset, the pressure-responsive bellows 16 elongates and by means of the rigid connection 15 it removes the needle valve 13 from its seat and thus opens the port 12. The liquid which is cooled in the coil 4 then passes through the port 12, expanding into chamber 5, and passes into the evaporator 7, where it becomes vaporized. The pressure of the evaporator rises, the bellows 16 contracts gradually and the needle valve 13 again closes the port 12. It can be seen that the bellows 16 thus tends to maintain the pressure in the evaporator at a constant and definite value.

The rigid connecting rod 19 makes the pressure-responsive bellows 16 integral with the thermostatic bellows 20. The bellows 20 is connected by a capillary tube 21 to a thermostatic bulb 22 disposed in thermal contact or heat exchange relation with the outlet of the evaporator 7, as shown. The assembly 20—21—22 contains a suitable expansible fluid which may be a liquid, a gas, or mixtures thereof. The different temperature conditions prevailing at the outlet of the evaporator create corresponding pressure changes in this thermostatic system. In addition, the bellows 20 is subjected externally to the atmospheric pressure and to the action of springs 14 and 23. Its length will, consequently, be modified by any variations in these various forces acting thereon, including changes in pressure within the bellows as a result of variations of temperature at the outlet of the evaporator. If the fluid introduced into the evaporator has not been entirely vaporized, the liquid will arrive in the suction line 8, causing it to coat with frost. The pressure-responsive bellows 16 does not act because the pressure remains constant for the entire duration of vaporization but the liquid in bulb 22 cools and the pressure drops in the bellows 20 so that it contracts under the action of spring 23 and against the action of spring 18, and accordingly seats valve 13. Port 12 is thus closed so that no fresh supply of fluid reaches the evaporator, whereupon the fluid that has already reached it will be able to vaporize completely. If, on the contrary, the fluid is already vaporized before leaving the evaporator 7, there will be a superheated vapor

at the outlet of the evaporator so that the temperature of the thermostatic bulb 22 will rise, increasing the pressure within the bellows 20; the bellows will expand and, outside of the temperature margin permitted by its adjustment, will lift the needle valve 13 from its seat so that a fresh supply of liquid will pass through the port 12 into chamber 5 and to the evaporator. This thermostatic bellows, consequently, tends to maintain conditions that will assure a maximum refrigerating effect from the evaporator.

In one practical example of an embodiment of this invention an increase of 7% was obtained in the refrigerating effect.

Two examples of practical embodiments of expanders that incorporate the features of this invention will now be described in connection with Figures 2 and 3. In these figures the reference numerals used in Figure 1 have been carried over to the corresponding elements.

The expander or pressure responsive device shown in Figure 2 is in its assembly similar to the one diagrammatically illustrated in Figure 1. It comprises a valve casing 30 of some suitable material, such as brass, which houses the member which contains the port or passage 12 controlled by the needle valve 13, also the pressure-responsive bellows 16 and the heat insulating bell or closure 31 of any suitable material, such as Bakelite, within which is the thermostatic bellows 20. The refrigerating fluid reaches the valve casing 30 through a threaded union 32 which screws into a pipe portion 33 forming part of the valve casing 30. The threaded union 32 is shown as having a threaded fitting 34 on its end for securing conduit 3 thereto.

The refrigerating fluid flows from the pipe portion 33 through a spiral passageway 4 formed in the casing member 35 and arranged in heat exchange relation with the chamber 5 of which the pressure-responsive bellows 16 forms a wall. The member 35 which surrounds the walls forming the chamber 5 provides the helical passage 4, which is in communication at its upper end with the conduit 33 and at its lower end through the passage 37 is in communication with the port 12. The annular member 35 in which the passage 4 is formed fits around a portion of the casing 30 as explained and is secured thereto at the joint 36 by welding or in any other suitable manner for forming a fluid tight seal.

A filter 38 of any suitable material, such as a fine metal mesh as, for example, a perforated brass sheet, is mounted in the piping portion 33 in order to remove from the incoming refrigerating fluid any solid impurities that might be present.

The aperture 12 is formed in an annular plug 39 made of a hard metal that is not readily attacked by the refrigerating fluids employed as, for example, it may be made of a very hard steel and the needle valve 13 of the same material. The plug 39 is threadedly mounted in a perforated supporting member 40 which in turn is threadedly mounted as shown in the casing 30. The member 40 is provided with a passage which communicates through a passage in the casing 30 with the passage 37 as shown. The perforated supporting member 40 is mounted in the central cross-stay 41 formed as a part of the housing 30. The fluid expands through the port 12, as will be apparent, and moves up into the chamber 5 through openings in the cross-stay 41. The refrigerating fluid leaves the chamber 5 through a threaded female union member as shown and passes to the evaporator, as previously explained.

The needle valve 13 is rigid with a plate 43 against which the helical spring 14 rests at one end. The other end of this spring engages a cap 44 which is threadedly mounted in a recess, as shown, in the casing 30. Secured to the plate 43 are three rods 17 disposed at the apexes of an equilateral triangle. The rods pass through openings in the cross-stay member 41 and are connected at their upper ends to the end plate 46 of the pressure-responsive bellows 16.

It will be obvious that these three connecting rods insure the lateral stability of the needle valve 13. To further insure the centering of the vertical path of movement of the needle valve, it is provided with a stem, as shown, sliding in the recess 78 formed in the cap 44.

The expansible bellows 16, which has been termed herein the pressure-responsive bellows, is preferably of an elastic material of some suitable metal alloy, as, for example, that sold under the trade name "Tombac." The necks of the bellows are very deep, as shown, and this increases its flexibility. In this way the bellows faithfully and accurately follows very small changes in pressure and assumes all of its positions by continuous variations without intermediate balancing. Its opposite end is engaged by an annular ring 48, preferably of metal, secured to the adjacent portion of the casing 30 in any suitable manner to form a seal and to the adjacent end of the bellows 16.

The upper end of the bellows 16 is closed or sealed from the space defined by the bell 31 by a member 49 preferably of Bakelite or other suitable material of poor heat conducting ability. The member 49 is preferably mounted in the bell by means of screw threads as shown. The member 49 has a passage, as shown, at its center through which the rod 19 extends which in turn is riveted, as shown, to the center of the closure plate 46 for the bellows. The rod 19 has an integral collar 50 against which one end of the spring 23 rests with its other end against the perforated end of the member 49. The member 49 when mounted in the bell 31 locks in place a plate or wall member 51 to define the lower wall of the chamber formed by the bell 31. The member 51 may likewise be made of heat insulating material so as to isolate the compartments and elements contained therein from heat exchange. The upper end of the rod 19 rests against a member 52 mounted in one end of the bellows 20 which in turn is housed in the bell 31 above the wall 51. The member 52 is mounted in the end or closure plate 53 sealed to the flexible wall of the bellows 20 as shown.

A device for limiting the movement of the bellows 20 is employed but it should first be noted that the other end of this bellows is sealed to a plate 54 which is secured at its center to a rod 55 forming part of the adjusting mechanism for the bellows. Mounted on the lower end of the member 55 and lying within the space defined by the bellows 20 is a tubular member comprising the half cylinders 56 and 57 which terminate at one end in the cam shaped head portions 58 and 59. Threadedly attached to the upper end of the abutment member 52, which is hollow, is a cap 60 which is perforated at the center by a passage the walls of which converge downwardly. Thus the cam shaped heads 58 and 59 may be passed through this passage when the half cylinders are compressed together and then separated to lock the tubular member in the position shown in Figure 2. By means of this arrangement, it will

be seen that the expansion or extension of the bellows 20 will be limited by the engagement of the cap 60 with the enlarged end of the tubular extension. On the other hand, the bellows is free to collapse without restraint from this device. Within the bellows is the spring 18 which rests at its ends against the closure caps 53 and 54 respectively of the bellows.

Extending through a central passage in the member 55 is the end 62 of the capillary tube 21 of Figure 1. The end of the tube 62 is sealed to the extension comprising the half cylinders 56 and 57 and the tube 62 in turn is sealed in the member 55 as indicated at 63 by welding or any other suitable manner.

The upper end of the member 55 is provided with threads 64 which threadedly engage a collar 65 mounted in the adjusting cap 66. Only axial movement of the member 55 is permitted by reason of the pin 67 mounted therein and projecting into a longitudinal groove 68 in the bell 31. Surrounding the member 55 is a packing means comprising the packing 69 and the adjustable sleeve 70 threadedly mounted in the upper end of the bell 31.

Thus it will be seen that the mechanism for closing the upper end of the bell 31 includes means for axially adjusting the member 55 and, consequently, the position of the end of the bellows 20 closed by the plate 54. The packing means forms a tight seal around the member 55 without interfering with its axial adjustment by rotating cap 66. This results from the fact that the cap 66 is provided with a screw 71 mounted in the metallic insert 72 in the cap 66 which, it may be noted is preferably of a suitable heat insulating material. This is the reason for forming the threads which engage the threads on the member 55 in a metal insert 65 molded into the cap 66. The end of the screw 71 engages in an annular groove 73 in the bell 31, as shown, so that the only movement which can result from the rotation of the cap 66 is the desired axial movement of member 55. This provides a simple arrangement for effecting the adjustment of means for controlling the superheating of the refrigerating fluid.

In addition to the parts made of insulating material as already mentioned, it may be noted that the rod 19 is also preferably made of a poor heat conductor such as Bakelite to further insure the heat insulation of the thermostatic bellows 20 against heat exchange with the surrounding atmosphere as well as protecting it against undue chilling by the refrigerating fluid in the chamber 5. Since the packing elements 69-70 separate the chamber 17 in bell 31 from the atmosphere, the operation of the entire unit will be stable in so far as variations in atmospheric pressure are concerned and independent of ambient temperature conditions.

The arrangement of Figure 3 employs in a large part the construction of the expander of Figure 2 below the wall 51. In this embodiment of casing or bell 31, the preliminary cooling circuit 4 and the pressure-responsive bellows 16 are of the same design as previously described and the details thereof are consequently indicated by the same reference numerals and further description thereof seems unnecessary. However, the thermostatic control is eliminated in this device. As a result the bell 31 is much shorter although it is provided, as before, with the packing elements 69-70 and the adjusting cap 66. The adjusting member 55 in this case serves for regulating the

pressure-responsive control of the expander and, therefore, rod 19 is modified as shown. The collar 50 is disposed nearer the lower end of the rod 19 and the compression spring 23 is interposed between its upper face and the end 75 of the member 55. The member 55 is provided with a counterbore 76 in which the upper end of the rod 19 may slide as the bellows 16 expands and contracts when subjected to pressure variations. The adjustment by cap 66 as before causes axial positioning of the member 55 and, therefore, varies the extent of compression of spring 23.

From the previous description of Figure 1, it will be understood how the expanders of Figures 2 and 3 operate and, therefore, no further detailed description of their operation seems necessary. As represented by two examples herein disclosed, it becomes apparent that those skilled in the art will readily appreciate that many variations and adaptations of the subject matter of this invention can be developed without departing from the novel subject matter thereof. I do not, therefore, desire to be strictly limited to the disclosure as herein given but rather to the scope of the claims granted me.

What is claimed is:

1. A method of refrigerating with a vaporizable refrigerating liquid in a refrigerating system having an evaporator, which comprises compressing the refrigerant to form a high pressure liquid, precooling the high pressure liquid in a first zone by conducting it therethrough in heat exchange relationship with low pressure liquid refrigerant in a second zone, expanding the high pressure liquid from said first zone into said second zone, after it has been precooled, to form low pressure fluid, conducting such low pressure fluid to the evaporator, and preventing the expansion of the high pressure liquid refrigerant whenever liquid refrigerant is leaving the evaporator.

2. A method of refrigerating with a vaporizable refrigerating liquid in a refrigerating system having an evaporator and an expansion valve, which comprises compressing the refrigerant to form a high pressure liquid, precooling the high pressure liquid by conducting it in heat exchange relationship with low pressure liquid refrigerant within said expansion valve, expanding the high pressure liquid through said expansion valve, after it has been precooled, to form low pressure fluid, conducting such low pressure fluid to the evaporator, opening the expansion valve in response to reduced pressure in the evaporator, and preventing the opening of the expansion valve, whenever liquid refrigerant is leaving the evaporator.

3. In a refrigerating system comprising a vaporizable liquid refrigerant, a compressor, an evaporator, and an expansion valve including a throttling port, means within said valve for precooling high pressure liquid refrigerant by conducting it in heat exchange relationship with low pressure liquid refrigerant before it passes through said port, and means responsive to the escape of liquid refrigerant from the evaporator for preventing the opening of said expansion valve.

4. In a refrigerating system comprising a vaporizable liquid refrigerant, a compressor, an evaporator and an expansion valve including a throttling port, means within said valve for precooling high pressure liquid refrigerant by conducting it in heat exchange relationship with low pressure liquid refrigerant before it passes through said port, means responsive to reduced pressure in said evaporator for opening said expansion valve, and means responsive to the escape of liquid refrigerant from the evaporator for preventing the opening of said expansion valve.

5. A device for use in refrigerating systems comprising an expansion valve including a casing and a throttling port therein, an inlet chamber within said casing through which refrigerant must pass before reaching said port, an outlet chamber within the casing through which refrigerant must pass after passing through said port, said inlet chamber surrounding and being in heat exchange relationship with said outlet chamber.

6. In a refrigerating system of the compressor-condenser-expander type employing an evaporator, the method of regulating the refrigeration cycle to give a maximum refrigerating effect in the evaporator which includes the steps of precooling high pressure liquid in a first zone by conducting it in heat exchange relationship with the liquid component of low pressure refrigerant in a second zone, and expanding the high pressure liquid from said first zone into said second zone after it has been precooled and before it is supplied to the evaporator.
